UNITED STATES PATENT OFFICE.

ERNEST L. BAULCH, OF MILLBURN, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 13, 1924. Serial No. 755,611.

This invention relates to telephone systems and particularly to improvements in systems employing what is known as straight-forward trunking between switchboards or exchanges.

In trunking systems of this type, calls are trunked by the so-called outward operators who receive the original calls and transfer them over the trunk lines to the so-called inward operators who extend the connections beyond to the wanted subscribers. Ordinarily, when receiving a call, the outward operator selects an idle trunk from a group of trunks leading to the desired exchange and supervises the extension of a connection over this trunk by the aid of a signaling circuit common to the group of trunks. A so-called distributor system of the start-stop distributor type is often used in connection with the common signaling circuit for the sending and receiving of supervisory signals in the form of codes. These code signals are translated into distinctive operations, which in case of signals sent to the inward operator, may cause the connection of the inward operator's telephone to the selected trunk and light a signal indicating to the inward operator the particular trunk selected or which may result in other supervisory signaling functions required in the setting up of a connection over trunks of this type.

The common signaling circuit may consist of an ordinary telephone line composed for telegraph use and in which one composite leg is used for transmission of supervisory signals in one direction and the other composite leg is used for transmission of supervisory signals in the opposite direction. A system disclosing the features as outlined above has been fully disclosed in Patent No. 1,578,651, issued to Karl M. Fetzer, March 30, 1926, and it is with an improved signaling circuit for a system of the above type that the present invention is concerned.

An object of the invention is, therefore, to provide a common signaling circuit for use in connection with straight-forward trunking systems, that is simple in design and inexpensive to install and maintain and in which the cost of the terminal devices provided in accordance with this invention is insignificant as compared with the cost of

the standard telegraph equipment at present employed for systems of this type.

Another object of the invention is to provide a common signaling circuit that can be easily arranged to function over any type of lines, such as composite or simplex lines, suitable for telegraphic transmission.

Another object of the invention is the provision of a common signaling circuit that is less sensitive to disturbances than ordinary telegraph equipments and thus thoroughly dependable in its operation under the most unfavorable line conditions.

To attain these objects in accordance with one feature of the invention there is provided means whereby the transmission of signals of a comparatively high voltage or current value may take place over one composite leg of a pair of telephone lines, simplex circuit or over any other line suitable for the transmission of telegraph signals in one direction and whereby the transmission of signals of the corresponding values may take place in the opposite direction over the composite leg of the same pair of telephone lines, another simplex circuit or over any other line suitable for the transmission of telegraph signals.

Another feature of the invention is the provision of terminal apparatus that transmits and responds to signals of a comparatively higher current value than are ordinarily used for telegraphic transmission.

Another feature of the invention is the provision of a simple and inexpensive network for each channel to eliminate any disturbing effect that the currents of higher values used in this system may have on adjacent lines. The installation of this additional network may be done without disturbing or in any way changing the existing standard networks of telephone lines composed or simplex for telegraph use.

The invention has been illustrated in the accompanying drawing in connection with a straight-forward trunking system employing a common signaling circuit and including the use of the so-called start-stop distributors for composing the various signals such as disclosed and described in the above mentioned patent. Only a portion of the transmitting distributor at one end and the receiving distributor at the opposite end for transmission in one direction has been

shown in detail, the remainder of the apparatus being merely indicated schematically. It should be understood that any system for originating and utilizing signals to be transmitted by means of the circuit arranged according to this invention may be employed and that the particular system indicated merely serves the purpose of illustrating how the invention is applied to an existing installation.

Referring now to the drawing, the portion marked 5 represents the signal composing equipment and the portion marked 6 represents the signal translating equipment at one end of the common signaling path 7, while the portions marked 9 and 10 represent the corresponding equipments at the opposite end of the path 7. Path 7 represents an ordinary telephone line composed for two telegraph channels 11 and 12 with telephone equipments 13 and 14 and the usual composite line networks 15 and 16 at opposite ends of the line. The relay 20 and network 21 constitute the terminal equipment arranged in accordance with this invention at one end of the path 7 for transmitting signals over composite leg 11 and relay 22, network 23, keys 24, 25 and 26 constitute the terminal equipment arranged in accordance with this invention at the opposite end of line 7 for the reception of signals incoming over composite leg 11. The corresponding transmitting and receiving terminal equipments for signals over the other composite leg 12 are correspondingly indicated by boxes marked 27 and 28.

The detail operation of the system will now be described in connection with signals transmitted from equipment 5 to equipment 9 over the composite leg 11.

It will be noted that relay 20 is normally energized in a circuit closed from negative battery, left hand winding of relay 20, segment 30, brush 31, segment 32 of distributor 33 to positive battery. This circuit maintains relay 20 energized in opposition to current through the right hand winding of the relay, the circuit for this winding being normally closed from negative battery to ground in such a manner as to cause the current in this circuit to oppose the current in the lower winding. The purpose of this biasing winding will be presently described. When now a signal is to be sent the start-stop magnet 34 is energized, due to actions taking place in the equipment indicated by box 46, and releases the arm 35 which thereby is free to rotate over the segments of the distributor 33 for one revolution for each code signal combination and then stopped by the pawl of magnet 34 which in the meantime has been released. As soon as brush 31 leaves segment 30, the energizing circuit for relay 20 is opened and relay 20 is released 65 under the influence of the current through

its right hand winding. The right hand winding, therefore, serves as a means to secure a quick release of relay 20 and as the operating characteristics of these two circuits and the battery supply can be readily adjusted as is well known in the art, they should remain constant for a great length of time. It is, therefore, readily seen that relays of this type, although simple in construction and inexpensive to manufacture, 75 will be highly reliable in performance. As the arm 35 proceeds to rotate, the brush 31 closes circuits from the positive battery at segment 32 to segments 40 to 45 in succession and in accordance with the particular code selected causes operations to take place in the equipment indicated by box 46 that will result in circuits being completed or not, as the case may be, from negative battery, 80 through the left hand winding of relay 20, to positive battery at 46 which is not shown here but which is provided as indicated in the above mentioned patent. That is, these functions will take place each time brush 35 passes over the segments 40 to 45. It therefore follows that relay 20 will be operated at varying intervals during the passing of brush 35 over the segments of distributor 33 to produce a distinctive code signal for each revolution of the arm 35. Upon each 85 operation therefore of relay 20, current from a negative battery will be supplied at the front contact and armature of relay 20 to the composite leg 11 and upon each release of relay 20 current from a positive battery 90 will be applied at the back contact and armature of relay 20 to the composite leg 11.

It will be noted that normally the negative battery at the front contact and armature of relay 20 is present on the line 11 to hold relay 22 energized. The circuit from this battery for relay 22 may be traced as follows: negative battery, armature and front contact of relay 20, network 15, windings of coil 21, composite leg 11, network 16, upper normally closed contacts of reversing key 24, left hand winding of relay 22, lower normally closed contacts of key 24, to ground. Relay 22 is also provided with a biasing winding, similar to the right hand biasing 110 winding of relay 20, through which current normally flows in a direction opposite to the normal operating current through the upper winding of this relay. With the circuits arranged in this manner, relay 22 will be operated and released in synchronism with the operation and release of relay 20, that is, when relay 20 is operated, negative battery through the armature and front contact will hold relay 22 operated in opposition to current through its right hand winding and when relay 20 is released, positive battery through the armature and back contact of relay 20 will cause relay 22 to release with the assistance of the current through its 115 120 125 130

lower winding. The first release of relay 22 closes a circuit from battery, start-stop magnet 50, segment 51, brush 52 of arm 55, segment 53 of distributor 54, lower normally closed contacts of key 25, upper normally closed contacts of key 26, armature and back contact of relay 22 to ground. This circuit causes the operation of start-stop magnet 50 which now releases arm 55 allowing it to rotate in synchronism with arm 35 of distributor 33 in a manner well known in the art. As relay 22 operates in synchronism with relay 20, impulses will, therefore, be transmitted or not, as the case may be, from battery through switching mechanism that interprets the code signal in the equipment indicated by box 56, through segments 57 to 61 in succession to segment 63, and from there through upper normally closed contacts of key 25, armature and front contact of relay 22 to ground. When now arm 35 reaches its normal position and is stopped by the pawl of magnet 34, the original circuit for relay 20 is again closed through segments 32 and 30 by brush 31, and consequently relays 20 and 22 are again operated. The operation of relay 22 causes the circuit for the start-stop magnet 50 to be opened and magnet 50 consequently released to stop the arm 55 in its normal position.

In order to save battery supply or rather to distribute the wear on the negative and positive batteries equally, the sending battery connections are often reversed so that instead of negative battery being normally connected to the line, positive battery will be so connected. When this is done all that the attendant has to do is to operate the reversing key 24 in order to hold relay 22 normally operated, that is, the terminals of the left hand winding of relay 22 are merely reversed so that the positive current will flow in the same direction through the winding as did negative current before the key was operated. The keys 25 and 26 are provided to cut out the receiving equipment 9 from line 7.

If these impulses alternately transmitted over leg 11 in opposite directions, were of a current value equal to that ordinarily used for metallic telegraph signals they would not be of sufficient strength to cause the operation of relay 22 or at least not able to operate this relay with any degree of dependability as the least disturbance on the line would interfere with the proper response of this relay. Ordinarily, therefore, in order to secure reliable results from low current values, expensive telegraph equipments had to be employed. To eliminate the use of such expensive equipments, the current values were increased and in accordance with this invention the above mentioned cheap relays substituted. It was found by actual practice that it was possible

to do this on existing comparatively short composite lines when the size of the wire was such as not to introduce a prohibitive impedance. It was also found that it could be done on existing short telephone lines 70 simplex for telegraphy where the size of the individual wires of a pair were such as not to permit the use of high current values for each wire, but where the combined size of the pair gives satisfactory results. In 75 this latter case, a different simplex line must, of course, be used for the transmission of impulses in each direction. An arrangement of this latter sort may also be used with advantage where a larger number of 80 telephone lines are available than could possibly be required for telegraph purposes and in such cases telephone lines may often be picked out in which the size of the individual wires are not suitable for transmission 85 of signals of this increased current but where the combined size of the line wires of a pair permits this to be done. In such instances, the existing number of telegraph channels need not, of course, be diminished. 90

Another advantage of this arrangement is also that very little change needs to be made in the existing standard networks used for duplexing or simplexing of telephone lines. In fact, all that has to be done is to add to each line at the sending end, a simple and inexpensive retardation coil and condenser wires to ground as shown at 21 or at 23, and it should be noted that the standard networks need not be changed or otherwise disturbed in any manner whatsoever. The purpose of these additional coils and condensers is to smooth out the impulses, that is, secure a more gradual increase and decrease of the current as it is applied to 100 the line so that no disturbing effects or so-called "thumps" will be detected in the adjacent wire of a pair of wires used for this purpose or in other adjacent pairs of wires 105 particularly if the lines are grouped in 110 cables.

Perhaps one of the principal advantages, in the long run of this system is its simplicity of maintenance over previous systems in which a specially trained telegraph apparatus attendant had to maintain and guard the Morse telegraph equipment, whereas in this case the attendant of the straight-forward trunking system involving this common signaling circuit will be able to maintain and guard the complete system as the 115 functions and general scheme of operation of this common signaling circuit are in line with the scheme of operation of the system as a whole. In this respect, therefore, its cost of maintenance is considerably reduced.

What is claimed is:

1. In a signaling system, a transmission line, a circuit for transmitting impulses including a transmitting branch, one conduc- 130

5   tor only of said transmission line and a receiving branch, said transmitting branch being connected between ground and said one conductor of said transmission line at one end of said transmission line, and said receiving branch being connected between ground and said one conductor of said transmission line at the other end of said transmission line, the impedance of said transmitting branch being greater than the combined impedances of the remaining elements of said circuit, whereby the fluctuation in potential values along said circuit due to the transmission of impulses is comparatively 10 small along said transmission line.

15   2. In a signaling system, a low impedance transmission line, a circuit for transmitting impulses including a high impedance transmitting branch, one conductor only of said low impedance transmission line and a low impedance receiving branch, a source of current and a transmitter at said transmitting branch for propagating impulses, and a device for receiving said impulses connected between said receiving branch and ground whereby the variation in potential along said circuit due to the transmission of said impulses is comparatively small along said transmission line.

20   3. A signaling system comprising a transmitter, a relay actuated thereby, a positive and a negative battery controlled by said relay, a two-conductor transmission line including a transmission network arranged for transmission of current impulses over each conductor independently, the relay being so connected to said transmission line that impulses from the said batteries are transmitted over one conductor only, a receiver responsive to said impulses at the op-

posite end of the conductor with which the relay is associated, an impedance connected between the relay and said conductor, and a condenser connected between ground and the mid-point of the said impedance.

25   4. A signaling system comprising a two-conductor transmission line including a transmission net work arranged for the transmission of telephone current over the said two conductors in series and direct current impulses over one conductor in one direction and over the other conductor in the opposite direction, positive and negative batteries, a relay connected to each end of each conductor, one for transmitting and the other for receiving impulses from said batteries, a transmitter at each end of said line arranged to control a corresponding relay to alternately transmit positive and negative direct current impulses from said batteries, the relay at one end transmitting impulses over one conductor and the relay at the opposite end transmitting impulses over the other conductor of said transmission line, a receiver at each end of said transmission line arranged to be controlled by a corresponding relay that receives impulses over the corresponding conductor, and impedance means arranged between each transmitting relay and its corresponding conductor, the impedance value of which and the corresponding conductor are so proportioned that comparatively high voltage direct current impulses may be transmitted over the conductor without causing any sudden increase in voltage on the conductor.

30   In witness whereof, I hereunto subscribe my name this 10th day of December, A. D. 1924.

ERNEST L. BAULCH,
